WALLET WITH EDGE STITCHED INNER POCKETS

Emil Karl Renz, Dedham, Mass., assignor, by
mesne assignments, to Debonair, Inc., Boston,
Mass., a corporation of Massachusetts.

Application March 31, 1944; Serial No. 528,933

1 Claim. (Cl. 150—38)

1

The present invention relates to pocket wallets made of leather, fabric or similar types of material which are provided with a long pocket for bills and notes extending the length of the wallet, and shorter pockets for cards and other materials. The pocket wallets of this general description embodying certain novel features are already disclosed and described in my copending applications, Serial No. 493,241, filed July 2, 1943, now Patent No. 2,366,875 and Serial No. 508,539, now Patent No. 2,439,579, Apr. 13, 1948, filed November 1943.

In the present invention particular attention has been paid to the construction of the inner side pockets attached to each half of the wallet and which normally, when the wallet is folded, have their outer surfaces lying in face to face relationship. For convenience that face of the wallet which is continuous and does not contain any pockets may be called the outer face or side of the wallet, and the other side on which the pockets may open transversely to the center of the wallet or in which the opening of the small pockets may be in relatively the same position as the opening for the bill fold, may be called the inner side of the wallet. It is highly desirable in all of these types of construction in accordance with the present invention to provide a continuous piece of leather or fabric for the entire outer face of the wallet, which leather piece will extend around the folded bend at the bottom edge of the wallet. This serves both to enhance the appearance of the wallet and also to provide a more flexible and more durable construction tending to stiffen the wallet on the center side in the two half sections adjoining the central section in which the wallet is folded. This type of construction is obtained in the present invention in different ways as will be more clearly shown from further description in the specification.

A further advantage which is gained in the present invention is that smaller pieces of material may be used in the construction, therefore making it possible to use pieces which otherwise might have to be scrapped. These and added features of construction will more readily be understood from the description given in the specification below when read in connection with the embodiments described in the drawings, in which—

Figure 1 shows a view of the wallet looking at the open inner face.

Figure 2 shows an enlarged fragmentary portion of the wallet shown in Figure 1 with certain additional constructional lines appearing dotted.

2

Figure 3 shows a view of a portion of the wallet looking at it from the front face with the front cover removed.

Figure 4 shows a section taken on the line 4—4 of Figure 2.

Figure 5 shows a section taken on the line 5—5 of Figure 3.

Figure 6 shows a fragmentary detail view in the construction and assembly of the wallet.

Figure 7 shows a perspective fragmentary view looking on the inside of the wallet between the outer cover and the inner stay.

Figure 8 shows a fragmentary view of a modification corresponding to the view of Figure 2, 15 and.

Figure 9 shows a section taken on the line 9—9 of Figure 8.

In the arrangement indicated in Figures 1 to 7 inclusive, the outer continuous face of the wallet is indicated at 1, and the inner side of the wallet contains a pair of flap pockets 2 and 3 on one half, and 4 and 5 on the other half, with additional full half pockets 6 and 7. The covers 8, 9 and 10, for the pockets 2, 3 and 6 respectively, are all attached to the turned edge of the outer face 1, and likewise the covers 11, 12 and 13, for the pockets 4, 5 and 7 are also attached to the turned edge of the outer face 1. The center divider 14 forming a partition facing the outer cover is also held in the bill fold section in a manner that will be described later. The inner face of the full half pockets 6 and 7 is formed by a stay member 15 which extends continuously in face to face relationship except for the intervening flaps 16 with the divider 14 and parallel in a normal position to the outer face 1. The stay member 15 forming the inner face or side of the pockets 6 and 7 is attached to inner folding flaps 16 (Fig. 7) which are extensions of the cover 10 and a corresponding inner folding flap which is an extension of the cover 13. This latter flap is not shown in the drawings since it is exactly like the flap 16, but on the other half of the wallet.

As indicated more clearly in Figure 4 which shows a section, the face of the wallet 1 extends around the lower edge in the portion marked 17 and is bent upwards a short distance on the front side of the wallet as indicated by the lower extension portion 18. The pocket covers 8, 9 and 10 are together supported by this marginal portion 18. The outer facing pocket 8 has its lower edge positioned parallel to and overlapping the marginal edge 18. The lower edge of the first inner pocket cover 9 is shown dotted in Figure 2.

by the line 19 which is parallel to the marginal edge of the portion 18 but is set above the lower edge of the face pocket cover 8 except in the anchor corner 20 where the edge 19 is extended downward to coincide with the lower edge of the facing pocket 8. In this way the stitching at the margin 23 only passes through two thicknesses of material and the pocket cover 9 is free except at the corner. The lower edge of the pocket cover 9 at 21 may be cemented on both the outer and inner sides, on the outer side to the facing cover 8 and on the inner side to the facing cover 10.

As has been previously stated the pocket cover 10 has an extension in the flap 16 which folds over the facing sheet forming between it and the pocket face 10, the pocket 6. This construction is the same for the both halves of the wallet shown in Figure 1.

The facing covers 8 and 10 are stitched to the marginal portion 18 by means of through stitching 22. This construction insures considerable flexibility for the wall section comprises the facing sheet 15 and the overlapping flaps one of which is indicated by the flap 16.

The divider 14 forms a partition in the bill fold section. This structure at the same time also provides considerable rigidity in the lower face of the pocket particularly in the two half sections at either side of the central fold. The appearance also at the inner side of the pocket provided by this assembly is similar to an embossed face with an attractive stitching at its edge. The wallet is also stitched at the side as indicated by the stitching 23, sewing together sheets 8, 9, 10 and the outer face 1 on the top side, as viewed in Fig. 1, and the corresponding sheets 11, 12 and 13 on the lower side thus making a durable and uniformly appearing construction at the edge of the inner face.

As shown in the figures the cover 9 extends diagonally over the cover 10 with the cover 8 cut in the same general manner but smaller, the two pockets 2 and 3 being closed only on the two outer edges.

In the construction and assembly of the inner portion of the pocket it will be noted that the sheet element or stay member 15 is provided at its lower edge, Fig. 6 with a slot 24 forming a strap member or loop 25 through which a tab 26 extending from the divider 14 is passed. This tab is slotted upward from the lower edge 27 of the stay member by means of the slots 28 and 29 so that when the tab 26 is threaded through the slot 24 on the inside of the strap 25, the two lower edges 27 of the divider 14 and 30 of the stay member 15 may be aligned together. The position indicated in Figure 6 is an intermediate position in the construction. When the tab 26 has been threaded through the slot and behind the strap 25, it is bent upwards as indicated in Figure 3 and cemented to the face of the divider 14. This construction anchors the divider 14 in the bill fold pocket at both ends of the bill fold since this construction is similar on both ends of the wallet. The facing or stay member 15 forming the inside of the pockets 6 and 7 is anchored as described in my copending applications mentioned above, with the facing or stay member 15 being provided with a slot forming a strap 31 at its side end and the flap 16 of the inner pocket cover 10 being slotted at 32 to provide a strip 33 which threads behind the strap 31 in the member 15. This construction as described in my copending applications, provides flexible adjust-

ment of the facing or stay member 15 to which the divider 14 is flexibly but firmly held. The pocket wallet therefore preserves its flexibility and permits the wallet to be folded about a center fold without causing any bulge in the leather when folded as usually occurs when a great number of bills are put into the wallet.

In the modification shown in Figures 8 and 9, a slightly different type of construction is used for the lower inner face edge of the wallet than that shown in the other figures. Also a different inner pocket construction of the inner facing side pockets is illustrated therein. In this construction on one half of the pocket wallet a complete half pocket is provided, similar to that indicated by the pocket 6 in Figure 1. This pocket is provided with a straight edge although other types of pockets may be used. As indicated at 40 this is formed by the outer facing cover 41 which folds over at the edge 42 and continues as an inner flap member similar to the flap 16 of Figure 7. The outer facing cover of the wallet extends the whole length of the wallet and is indicated in Figure 9 by 43. In the view of Figure 8 however, this outer face is viewed from the inner side.

The outer face 43, (Fig. 9) extends around the lower edge as indicated at 44 to the inner face side of the wallet in the extending margin portion or strip 45 which is bent in a sharp bend at 46 to which the inner face pocket elements are stitched. The assembly of this portion of the pocket is finished before the portions 44, 45 and 46 are turned in the position shown in Figure 9. The inner pockets in the structure shown in Figure 8 and Figure 9 comprise a small attached purse pocket book 47 which may be provided with accordion folds 48 and 49 at the sides and a top envelope flap 50 with a snap clasp 51 buttoning into its component part in the cover 52 of the face of the purse. This whole assembly is sewn to the facing flap 41 on its outer surface. The lower edges of the purse pocket 47 and the lower edge of the facing member 41 are stitched together with the outside cover 43. As has been mentioned above this is assembled before the outside face has been turned in the position shown in Fig. 9. The sheet 43 is simply laid over in face to face relation with the purse pocket face 52 of the purse 47 and with the lower edges of the face 52 and 41 lined up with the lower edge 53 of the sheet 43. These sheets are then stitched together by stitching 54 and thereafter the sheet 43 is turned around the bottom edges of the faces 52 and 41 to the position indicated in Figure 9. In this position the outside face is stitched to the other faces in the side stitching 55. This construction provides the effect of an embossing at the lower edge of the pocket book on the inside face giving rigidity to this face and forming strength for the base of the pocket purse structure formed on the inner face of the wallet. This type of construction is particularly useful for ladies' wallets providing a means for holding small change in the wallet. Combinations with different colors for different prices may be used.

Having now described my invention, I claim:

A pocket wallet of the type described, comprising an outer wall and an inner wall, the inner wall comprising a stay member extending substantially the length of the wallet, flap members positioned at each end of the wallet, said flap members each having an extension folding over the top edge of the stay member and secured by a lost motion connection to the stay member at

the ends of the wallet, a pair of cover members positioned substantially parallel to said flap member on one half of the wallet, the outer of said cover members and said flap member being co-extensive with the end and bottom edge of the outer wall, the inner of said cover members having its lower edge cut short along the bottom edge except for a place at the end of the edge farthest from the end of the wallet, and a line of stitching at the end and bottom edges of the wallet securing the edges of the outer wall, flap member, and cover members along their end and bottom edges except for the cut out portion of the inner cover member.
